UNITED STATES PATENT OFFICE.

GEORGE H. STEVENS, OF WOODBURY HEIGHTS, NEW JERSEY.

GAS-BURNER.

1,350,678.

Specification of Letters Patent.

Patented Aug. 24, 1920.

Application filed October 29, 1919. Serial No. 334,120.

To all whom it may concern:

Be it known that I, GEORGE H. STEVENS, a citizen of the United States, residing at Woodbury Heights, county of Gloucester, 5 State of New Jersey, have invented a new and useful Gas-Burner, of which the following is a specification.

My present invention relates to a gas burner wherein there is employed a pyrophorous metal alloy adapted to be abraded by a suitable substance such as for example a steel wheel having an irregular surface or serrations at its periphery.

In devices of this character as heretofore constructed, the shock incident to the operation of the igniting device often causes the loosening of the burner tips and in some cases causes them to become broken.

One object of my present invention is to devise a construction which will overcome the excessive shock which has heretofore been present in devices of this character, thereby eliminating the loosening or breaking of the burner tips.

Another object of my invention is to devise a novel construction of a releasing mechanism which is not dependent upon the strength or condition of a spring or other member which is subject to change of shape 30 or strength and to provide a novel construction of controlling mechanism so that the releasing mechanism is set into operation at a predetermined point.

With the above and other objects in view as will be hereinafter more fully set forth in the detail description, my invention comprehends a novel construction of gas burner and a novel construction of ignition means for the burner.

It further comprehends a novel construction and arrangement of a shock absorbing member and novel means for releasing it at the proper time.

It further comprehends a novel construction for supporting and operating the abrading member including a novel construction of cams and novel means for operatively connecting them together.

It further comprehends a novel construction of a burner casing, a novel construction and arrangement of an igniting device and novel means for operating the valve mechanism for the burner in such a manner that

the gas is permitted to escape in time to reach the outlet from the burner prior to 55 the sparking of the pyrophorous metal.

Other novel features of construction and advantage will hereinafter more clearly appear in the detailed description of the invention.

For the purpose of illustrating my invention, I have shown in the accompanying drawing a typical embodiment which is at present preferred by me, since the same will give in practice satisfactory and reliable results, although it is to be understood that the various instrumentalities of which my invention consists can be variously arranged and organized and that my invention is not limited to the precise arrangement and organization of these instrumentalities as herein shown and described.

Figure 1 represents, in front elevation, a gas burner embodying my invention.

Fig. 2 represents a side elevation of the 75 burner.

Fig. 3 represents a section on line 3—3 of Fig. 2.

Fig. 4 represents a section on line 4—4 of Fig. 3.

Fig. 5 represents a plan view of one of the cams in detached position the shaft on which it is mounted being shown in section.

Fig. 6 represents, in side elevation and on an enlarged scale, a portion of the burner.

Fig. 7 represents a bottom plan view of a portion of the mechanism showing more particularly the manner in which the valve and the shaft of the igniting device are intergeared.

Similar numerals of reference indicate corresponding parts.

Referring to the drawings,

The casing of the burner for simplicity in manufacture is preferably made of two parts, the main body portion 1 and the auxiliary body portion 2 in the form of a bracket. The body portion 1 has mounted in it a one-way valve 3 to one end of which is connected a gear segment 4 which meshes 100 with a gear segment 5 which is fixed to a shaft 6. This shaft 6 is journaled in a plate 7 which is clamped to the body portion 1 as well as the laterally extending flange 8 of the bracket 2 by means of a threaded 105 pillar 9 in threaded engagement with the

body portion 1. The pillar 9 carries in the usual manner the burner tip 10. The flange 8 has opposite sides downwardly deflected as at 11 so as to closely engage the sides of the body portion and prevent any lateral movement of the bracket 2 or the plate 7 relatively to the body portion 1. The shaft 6 has connected to it in any desired manner the actuating handle 12. The shaft 10 6 above the plate 7 has fixed to it a cam 13 the construction of which is best seen in Fig. 5. This cam 13 is provided with a shoulder 14, a recess 15, a shoulder 16, a face 17, a cam face 18 and a recess 19.

15 20 designates a sleeve or cylinder which has a reduced neck 21 journaled in the laterally extending upper portion 22 of the bracket 2. Above the neck 21 the sleeve 20 is provided with the polygonal shaped portion 23 from which extends upwardly an internally threaded tube 24. The polygonal shaped portion 23 interlocks with a recess of corresponding contour in a disk 25 so that this disk 25 is fixed with the sleeve 20. The 25 disk 25 has mounted on its upper face a coil spring 26 which engages with the teeth of the ratchet 27 formed on the under side of a friction wheel 28 which is loosely mounted on the internally threaded tube 24 which latter forms a bearing for the friction wheel. A screw 29 in threaded engagement with the tube 24 retains the friction wheel in assembled position.

30 The flange 22 of the bracket 2 is extended upwardly and forms the container 30 to receive the stick 31 of pyrophorous metal alloy. The retainer 30 is provided with a slot 32 into which the upper end of a rock arm 33 extends, the rock arm being pivotally supported at 34 on the bracket 2 and a spring 35 is provided which tends to move the upper end of the rock arm 33 inwardly so that the sparking alloy will be retained in contact with the serrated periphery of the friction wheel. The sleeve 20 has fixed to its lower end a cam 36 which is provided with a pin 37 which extends into the recess 15 of the cam 13 so as to be positioned between the shoulders 14 and 16. The cam 36 is provided with a peripheral recess 38, the cam face 39 and a shoulder 40.

45 50 55 60 65 41 designates a shock absorbing spring one end of which is secured to an extension of the bracket 2 by means of a rivet or other fastening device 42 and the bracket is provided with outwardly extending ears 43 which serve as guides for the spring 41. The free end of the spring 41 is inwardly deflected to form a rounded contact portion 44. It will of course be understood that the body portion 1 is suitably internally threaded in order to adapt it to be connected to the ordinary gas fixture. The shaft 6 has connected to it one end of a spring 45 the other end of which is fixed to a sleeve 20 in any de-

sired manner, for example, by passing through an aperture in said sleeve as shown in Fig. 3.

The operation of my novel construction of gas burner will now be apparent and is as follows:

When the parts are in the position seen in Fig. 1, the valve 3 is in closed position and the spring 45 is under tension. The sleeve 20, however, is prevented from rotating since the contact portion 44 of the spring 41 engages the recess or indentation 38 of the cam 36.

60 65 70 75 80 85 90 95 100 105 110 115 120 The operator turns the handle 12 in a clockwise direction and owing to the provision of the intermeshing gear segments 4 and 5 the cam 13 will be turned and the cam face 18 engaging the rounded contact portion 4 of the spring 41 will move it outwardly so that it is released from its engagement with the recess 38 of the cam 36 whereupon the sleeve 20 will revolve at a relatively high speed due to the tension of the spring 45 and the pawl 26 which is in engagement with one of the teeth of the ratchet wheel 27 carried by the friction wheel 28 to cause the friction wheel to revolve a quarter turn so that the desired sparks will be produced by contact with the stick 31 of pyrophorous metal. The releasing mechanism for the sleeve 20 which effects the operation of the friction wheel is operated at a predetermined time without regard to the strength or condition of a spring or other member subject to change of strength or shape. The parts are arranged in such a manner that the gas is permitted to escape in time to reach the outlet from the burner tip before the sparking of the pyrophorous metal takes place. The undue shock which is ordinarily present in devices of this character is eliminated in my present construction by the action of the shock absorbing spring 41, the contact portion of which engages the recesses 19 and 40 in order to absorb the shock.

110 115 120 125 130 In order to turn off the gas the operator turns the handle 12 in a counterclockwise direction thereby turning the cam 13 in a counterclockwise direction and the shoulder 14 engaging the pin 37 causes the cam 36 and the sleeve 20 to be returned to their initial position at which time the contact portion 44 of the spring 41 interlocks with the recess 38 of the cam 36. This operation also rotates the valve 3 to bring it into its closed position.

125 130 135 140 145 The friction wheel 28 forms an abrading member and since there is no relatively slow movement of the abrading member the sparking alloy is consumed only for producing sparks when needed.

140 145 150 155 160 It will be seen that when the grasping handle is operated to bring the operating spring 45 under tension, the valve 3 is moved into its closed position.

It will now be apparent that I have devised a novel and useful construction of a gas burner which embodies the features of advantage enumerated as desirable in the

5 statement of the invention and the above description, and while I have, in the present instance, shown and described a preferred embodiment thereof which will give in practice satisfactory and reliable results, it is to

10 be understood that such embodiment is susceptible of modification in various particulars without departing from the spirit or scope of the invention or sacrificing any of its advantages.

15 Having thus described my invention, what I claim as new and desire to secure by Letters Patent, is:—

1. In a gas burner, the combination with the burner proper having a valve controlled 20 inlet, of an abrading wheel, pyrophorous metal in contact with said wheel, a spring actuated device to revolve said wheel, and shock absorbing means for said device to retain it in position to be released and to 25 absorb the shock resulting from its being released.

2. A gas burner having a valve controlled inlet, an abrading wheel rotatably mounted, pyrophorous metal coöperating 30 with said wheel, a cam to effect rotation of said wheel, a tension device, means to rotate said cam and actuate said valve, a second cam to release said first cam, and a shock absorbing device coöperating with 35 said cams.

3. A gas burner, comprising a burner proper, a valve controlling admission to the burner proper, a shaft intergeared with said valve, a cam on said shaft, a member rotatably mounted, a pawl carried by said member, a cam on said member, a tension device

for said member, spark producing mechanism actuated by said member, a shock absorbing device coöperating with the cam of said member and actuated by the cam on 45 said shaft to release said member when under tension, and means coöperating with said cam to effect the return of said member to its initial position.

4. A gas burner, comprising a burner proper, a valve controlling the admission of gas to the burner proper, a shaft operatively connected with said valve to open and close it, a sleeve loosely mounted on said shaft, a tension device for said shaft, 50 spark producing mechanism actuated by said sleeve, a cam on said sleeve, a spring engaging said cam to retain said sleeve in tensioned position, a cam on said shaft having means to release said spring when rotated, and means to actuate said shaft.

5. A gas burner, comprising a burner proper, a valve controlling the flow of gas to said burner, a shaft connected to said valve to actuate it, a sleeve loosely mounted 65 on said shaft, spark producing mechanism actuated by said sleeve, a cam on said sleeve having an outwardly extending pin, a cam fixed to said shaft and having a recess into which said pin extends, the cam on said 70 shaft having a shoulder, and a spring co-operating with said cams, said spring co-operating with the cam on said sleeve to retain it in position, a cam on said shaft co-operating with said spring to release it from 75 the other cam, and means to actuate said shaft.
